UNITED STATES PATENT OFFICE.

CLARENCE J. RODMAN, OF ALLIANCE, OHIO.

LIFTING JACK.

Application filed July 27, 1927. Serial No. 208,736.

This invention relates to jacks, and particularly to a screw jack having an improved reinforced housing.

I provide a screw jack having a base with a housing projecting therefrom, the housing being effective for supporting suitable guideways which cooperate with a lift member. The housing is also effective as a guard for the lift screw. The base is preferably provided with an operating shaft having a bevel pinion thereon, the pinion engaging a bevel gear fastened to the lifting screw. The bevel gear is supported preferably upon an anti-friction bearing which takes the load applied to the screw.

The housing and the lift member are so constructed that the binding of the screw, which is quite frequent in jacks of this type, is entirely eliminated. It is found in practice that the jack operates very smoothly and easily because of this fact.

In the accompanying drawings, illustrating a present preferred embodiment of my invention:

Figure 1 is a side elevation of a jack embodying my invention;

Figure 2 is a sectional view on the line II-II of Figure 1;

Figure 3 shows the jack with a handle in operating position; and

Figure 4 illustrates the handle shown in Figure 3 in collapsed position.

Referring to the illustrated embodiment there is shown a jack having a base 2 with an upstanding housing 3 made integral therewith. A reinforcing rib 4 lying alongside the housing 3, extends substantially the full length of the housing and terminates in a reinforcing rib 5 which extends around the upper end of the housing 3.

Guideways 6 made integral with the housing 3 and the base 2 extend the full length of the housing, and are turned outwardly therefrom to serve as reinforcing ribs, as well as guideways.

Disposed substantially intermediate of the guideways 6 is a lift screw 7. A bevel gear 8 lies within the hollow base 2 and is secured to the lift screw 7. The screw 7 and the gear 8 are fastened together in such manner that the load imposed upon the screw is carried by the bevel gear 8. The gear 8 rests on a roller bearing 8^a which takes the full load of the jack, and reduces the turning moment necessary to operate the jack.

The gear 8 is driven by a bevel pinion 9 supported on a shaft 10, extending through a bearing portion 11 formed in the housing 2. The outer end of the shaft 10 is engaged by a collar 12 which is shaped to receive a suitable operating handle 13.

Slidably mounted on the guideways 6 is a lifting member 14, provided with a nut portion 14^a which engages the lifting screw 6. The nut portion 14^a is preferably disposed at the lowermost end of the lifting member 14 in order to provide the greatest possible effective operating height.

The lifting member 14 is provided with channeled side portions 15, adapted to operate on the guideways 6. The channels 15 are interconnected by a substantially semi-circular portion 16 extending the full length of the lifting member and serving to house the active portion of the lifting screw. The lifting member 14 is reinforced by a T-shaped rib 17 extending substantially the full length of the lifting member. The head 18 of the T joins a lifting saddle 19 formed on the top of the lifting member 14, to reinforce the same. The outer face of the head 18 is provided with teeth 20. These teeth support a lifting foot 21 which is movable up and down the lifting member as desired. The lifting foot 21 has a pair of arms 22 which embrace the T rib 17, the arms 22 having lugs 23 which fit behind the head 18 of the T rib. The lifting foot 21 is also provided with a stop 24 which engages the supporting teeth 20. The construction shown is found in practice to eliminate the customary binding of the screw. It is also of advantage in that the lift member 14 lies in such close proximity to the screw that there is a minimum overhang, and therefore, a minimum bending moment when a load is applied to the lifting foot 21.

A short rib 25 extending from the rounded portion 16 to the flange of the T rib 17 prevents the foot from dropping off the lifting member. The lifting foot may be inverted on top of the lifting saddle 19 and so provides additional effective lifting height. It will be noted that the channels 15 merge into the saddle 19 and are closed at the upper end, thereby preventing dirt from falling onto the guideways. This construction also provides additional strength.

The jack is particularly adapted for automobile work by reason of its ease of operation

and comparatively large mechanical advantage. The two ribs 6 acting on the channels 15 easily resist the turning moment imparted to the lifting member. It will be understood that in operation the base may tend to rotate, and that this is resisted by friction of the base on the ground and by the engagement of the lifting member on the automobile being lifted. If the base should tend to turn, the action of the lifting member on the automobile is sufficient to prevent turning of the jack and, as above stated, the ribs 6 acting in the channels 15 effectively resist relative rotational movement of one part 15 on the other. The jack is rendered particularly strong by reason of the housing and guideways being formed integrally with the base; likewise that portion of the base which surrounds the operating pinion 9 serves to 20 strengthen the connection between the housing and the base.

The base 2 has an extension plate 26 which, resists the bending moment set up by heavy loads carried on the lifting foot 21. 25 The extension plate 26 is made of wrought metal such as steel plate. This provides a strong extension foot which requires a minimum of head room. It is not subject to breakage as a casting would be.

30 As shown in Figure 3, the jack is preferably operated by means of a handle terminating in a crank 27, the handle 13 being of such length that the jack is readily operable in various positions under an automobile or other desired load, and the crank 27 being of such dimensions that the mechanical advantage obtained is commensurate with the normal load of the jack. The handle 13 is hinged so that it may be 40 folded into a conveniently small space when not in use. The operating end of the handle 13^a is provided with wings 13^b which are rounded so that the exterior edges 13^c thereof are narrower than the portions adjacent the handle proper. This permits the crank to be operated with the handle extended at various angles to the jack without danger of the wings 13^b becoming wedged within the socket 12 on the end of the pinion 45 shaft 10. As described in my copending application aforesaid, the socket 12 is hollow and has an annular recess 28 formed internally thereof, the recess being blocked at diametrically opposite points by bosses 50 adapted to engage the wings 13^b. Access to the interior of the socket is provided by an opening 29 (Figure 2) conforming with the contour of the winged end of the handle 13. Slots 29^a forming a portion of the opening 55 29 and adapted to receive the wings 13^b are disposed at substantially a right angle to the interior bosses which obstruct the free turning of the wings in the annular recess 28. Thus the handle may not be withdrawn 60 directly from the socket when it is in op-

erating position, and the jack may be maneuvered into a desired position with the handle.

While I have illustrated and described a preferred embodiment of the invention, it 70 will be understood that it is not thus limited, as it may be otherwise embodied within the scope of the following claims.

I claim:

1. A jack comprising a base having guideways projecting therefrom, a lifting member adapted to slide on the guideways, said lifting member comprising channel portions adapted to cooperate with the guideways, a member connecting the channel portions and 80 a T rib disposed on the member substantially intermediate the channel portions, said T rib extending substantially the length of the channel portions, and a lifting saddle on top of the connecting member, said saddle being 85 a continuation of the head of the T rib.

2. A jack comprising a base having a pair of guideways projecting therefrom, a lifting screw intermediate the guideways, a substantially semicircular housing connecting 90 the guideways and partially enclosing the screw, a lifting member adapted to slide on the guideways, said lifting member comprising a pair of channel portions cooperating with the guideways, a substantially semicircular member connecting said channel portions and enclosing the lifting screw, and a lifting saddle on top of the connecting member, the saddle being integral with the channel portions and connecting member. 95

3. A jack comprising a vertically extending open sided housing, the edges of the housing adjacent the open side thereof forming guideways, a recessed open sided lift member having its edges adjacent the open side adapted to co-operate with the guideways, and a lifting screw enclosed by the housing and the lift member. 100

4. A jack comprising a pair of cooperating open sided recessed members, one of said members being slideable on the other, the open sides of the members facing one another so as to define an enclosed space, and a lifting screw in the space. 110

5. A jack comprising a pair of cooperating open sided recessed members each substantially semi-circular in cross section, the edges of one of said members having guideways formed thereon, the other having its edges formed to cooperate with such guideways so 115 that the members are slideable on one another and cooperate to define an enclosed space of generally circular cross section, and a lifting screw in such space, the lifting screw being carried by one of the members 120 and engaging the other so as to cause relative movement therebetween. 125

In testimony whereof I have hereunto set my hand.

CLARENCE J. RODMAN.

CERTIFICATE OF CORRECTION.

Patent No. 1,719,084.

Granted July 2, 1929, to

CLARENCE J. RODMAN.

It is hereby certified that error appears in the printed specification of the above numbered patent requiring correction as follows: Page 2, line 15, after the word "other" and period insert the words "The guideways 6 also serve as reinforcing ribs."; and that the said Letters Patent should be read with this correction therein that the same may conform to the record of the case in the Patent Office.

Signed and sealed this 30th day of July, A. D. 1929.

(Seal)

**M. J. Moore,
Acting Commissioner of Patents.**
